UNITED STATES PATENT OFFICE.

FRANK X. STAUB, OF FORT WAYNE, INDIANA, ASSIGNOR TO CORWIN TELEPHONE MANUFACTURING COMPANY, OF CHICAGO, ILLINOIS, A CORPORATION OF ILLINOIS.

TELEPHONE SYSTEM.

977,142.

Specification of Letters Patent. Patented Nov. 29, 1910.

Application filed April 8, 1910. Serial No. 554,097.

To all whom it may concern:

Be it known that I, FRANK X. STAUB, citizen of the United States, residing at Fort Wayne, in the county of Allen and State of Indiana, have invented a certain new and useful Improvement in Telephone Systems, of which the following is a full, clear, concise, and exact description, reference being had to the accompanying drawings, forming 10 a part of this specification.

My invention relates to telephone systems and has for its object the provision of an improved circuit arrangement and apparatus whereby telephone receivers equipped with 15 soft iron readily magnetizable and demagnetizable cores may be energized by means of direct current passed over the lines leading to the telephone stations including such receivers. In accordance with the preferred 20 embodiment of my invention, when a line is idle, the soft iron core receiver is not included in circuit with the source of direct current but when this line is employed for conversational purposes, the source of direct 25 current is included in circuit with the receiver. The telephone transmitter at each station equipped with a soft iron core receiver is desirably directly included in the telephone line, but I do not wish to be limited 30 to this characteristic. Multiply related paths, each serially included in the line, are provided at the telephone station equipped with the soft iron core receiver, one of these paths desirably containing all of the receiver 35 voice current winding while the other path is substantially non-inductive. The two multiply related paths are so proportioned as to enable the source of direct current, such as a battery, properly to magnetize 40 the core of the receiver so as to make it perform the function of a permanent magnet and at the same time be properly responsive to voice currents coming in over the line, the substantially non-inductive shunt permitting 45 voice currents impressed upon the line by the operation of the transmitter at the same station with the receiver to be shunted away from the receiver winding to a sufficient extent to enable them properly to 50 be impressed upon the line. The substantially non-inductive shunt provided about the receiver winding may be metallically continuous, in which case a non-inductive coil of a resistance which is desirably high with respect to the receiver winding is provided.

If preferred, the non-inductive shunt may include a condenser in place of the non-inductive coil.

I will explain my invention more fully by reference to the accompanying drawing 60 showing the preferred embodiment thereof, in which—

Figure 1 illustrates a telephone line extending from a substation to an exchange and Fig. 2 illustrates a telephone line such as 65 may be found, for example, in interior systems.

Like parts are indicated by similar characters of reference throughout the different figures.

Referring first to the equipment illustrated in Fig. 1, I have shown a telephone line whose limbs *a b* extend from a telephone station *A* to an exchange *B*, the limbs *a b* terminating respectively in short and long 70 line jack springs *c d* that are illustrated respectively in engagement with the tip and sleeve of a cord circuit plug *e*. The cord circuit strands include condensers *f* and *g* shunted respectively by the pair of impedance coils *f'* and the pair of impedance coils *g'*, a battery *h* of from twenty to sixty volts or other suitable voltage having one pole connected between the impedance coils *f'* and the other pole connected between the 75 impedance coils *g'*. I have not illustrated any more of the cord circuit apparatus nor any more of the line equipment, as such apparatus is well known by those skilled in the art. When a jack receives a plug thus 80 connected with a source *h* of direct current, the current may flow over the line, assuming that the telephone of such line is removed from its switch hook, a switch hook *i* being illustrated at the substation *A*. When the 85 switch hook is relieved of the weight of the receiver, it joins the two sides *a b* of the telephone line through a transmitter *k* and the winding *l* of a telephone receiver serially related with the transmitter, this winding surrounding a soft iron readily magnetizable and demagnetizable core which is magnetized by the current of the battery *h* to enable 90 it to have the function of a permanent magnet and which is at the same time subject 95 to incoming voice currents traversing the winding *l* to enable the receiver telephonically to respond. A substantially non-inductive shunt circuit *m* surrounds the receiver winding but is serially related with 100 105 110

the transmitter so as to reduce the impedance offered by the winding l to the voice currents impressed upon the line at the transmitter h , said shunt circuit being so proportioned as to cause the voice currents coming in to the receiver over the telephone line properly to pass through the receiver winding l to occasion the efficient operation of the receiver.

10 In the form of the invention illustrated in Fig. 1, the substantially non-inductive shunt circuit is metallically continuous and includes a non-inductive winding n that may be, for example, of five hundred ohms resistance in event of the receiver winding l being of one hundred ohms resistance. By the relative proportions of resistance specified, the receiver may readily be magnetized by direct current from the battery h and

15 will readily respond to incoming voice currents while the impedance offered to outgoing voice currents is sufficiently reduced to enable the proper propagation of outgoing voice currents.

20 25 The arrangement shown in Fig. 2 is in all essential respects similar to the arrangement shown in Fig. 1, the battery being connected directly with the line through the impedance coils f' g' without the aid of plug and jack, while at the telephone station equipped with a soft iron core telephone receiver, the substantially non-inductive shunt about the receiver winding l includes a condenser o that may be of one half microfarad

30 35 capacity in place of the substantially non-inductive winding n belonging to the system illustrated in Fig. 1.

While I have herein shown and particularly described the preferred embodiment of my invention, I do not wish to be limited

to the exact details of construction shown as changes may readily be made without departing from the spirit of the invention, but,

Having thus described my invention, I claim as new and desire to secure by Letters Patent the following:

1. A telephone system including a telephone line having a telephone station which includes a receiver having a soft iron readily magnetizable and demagnetizable core provided with a winding serially included with the line and with means at the same station with the receiver for impressing voice currents upon the line; a substantially non-inductive shunt about turns of the receiver winding and also serially related with said means; and a source of direct current included in circuit with the receiver winding by the telephone line.

2. A telephone system including a telephone line having a telephone station which includes a receiver having a soft iron readily magnetizable and demagnetizable core provided with a winding serially included with the line and with a transmitter at the same station with the receiver for impressing voice currents upon the line; a substantially non-inductive shunt about turns of the receiver winding and also serially related with said transmitter; and a source of direct current included in circuit with the receiver winding and the transmitter at the same station therewith by the telephone line.

In witness whereof, I hereunto subscribe my name this 2nd day of April A. D., 1910.

FRANK X. STAUB.
